US00D956707S

(12) **United States Design Patent** (10) **Patent No.:** **US D956,707 S**
(45) **Date of Patent:** **** Jul. 5, 2022**

(54) **CIRCUIT BOARD**

(71) Applicant: **LAPIS Semiconductor Co., Ltd.**,
Yokohama (JP)

(72) Inventor: **Shigeki Yamauchi**, Yokohama (JP)

(73) Assignee: **LAPIS SEMICONDUCTOR CO., LTD.**, Yokohama (JP)

(**) Term: **15 Years**

(21) Appl. No.: **29/729,267**

(22) Filed: **Mar. 25, 2020**

(30) **Foreign Application Priority Data**

Sep. 26, 2019 (JP) 2019-21604
Sep. 26, 2019 (JP) 2019-21605
Sep. 26, 2019 (JP) 2019-21606

OTHER PUBLICATIONS

Japanese Office Action dated May 12, 2020, for related Japanese Appln. No. 2019-021606 4 Pages.

Primary Examiner — Elizabeth J Oswecki

(74) Attorney, Agent, or Firm — Brooks Kushman P.C.

(57) **CLAIM**

The ornamental design for a circuit board, as shown and described.

DESCRIPTION

FIG. 1 is a front view of a circuit board showing my new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

Throughout the drawings, the dash-dash broken lines are for the purpose of illustrating environment only and form no part of the claimed design.

1 Claim, 2 Drawing Sheets
